UNITED STATES PATENT OFFICE.

FREDERIK G. WHITTINGTON, OF EVANSTON, ILLINOIS, ASSIGNOR TO STEWART-WARNER SPEEDOMETER CORPORATION, OF CHICAGO, ILLINOIS, A CORPORATION OF VIRGINIA.

DESIGN FOR AN INSTRUMENT DIAL PLATE.

Application filed March 20, 1922. Serial No. 1,283. Term of patent 14 years.

To all whom it may concern:

Be it known that I, FREDERIK G. WHITTINGTON, a citizen of the United States, residing at Evanston, in the county of Cook and the State of Illinois, have invented a new, original, and ornamental Design for an Instrument Dial Plate, of which the following is a specification, reference being had to the accompanying drawing, forming a part thereof.

The drawing is a face view of an instrument dial plate embodying my new design.

I claim:

The ornamental design for an instrument dial plate as shown.

In testimony whereof I have hereunto set my hand at Chicago, Illinois, this 2nd day of March, 1922.

FREDERIK G. WHITTINGTON.
